CLAIM

The ornamental design for a simultaneous compression, tension, and movement therapy device, as shown and described.

DESCRIPTION

FIG. 1 is a front three-quarters left perspective view of a simultaneous compression, tension, and movement therapy device.

FIG. 2 is a top view thereof.

FIG. 3 is bottom view thereof.

FIG. 4 is an enlarged front view thereof.

FIG. 5 is an enlarged rear view thereof.

FIG. 6 is a right side view thereof.

FIG. 7 is a left side view thereof.

FIG. 8 is an enlarged bottom three-quarters perspective view thereof.

FIG. 9 is an enlarged side three-quarters perspective view thereof with the bottom member removed for ease of illustration; and,

FIG. 10 is an enlarged side perspective view thereof.
